DESIGN FOR A BLANKET

Joseph L. Kyle, Glendale, Long Island, N. Y., assignor to Whittenton Manufacturing Company, Boston, Mass., a corporation of Massachusetts

Application May 9, 1933. Serial No. 48,057

Term of patent 14 years

To all whom it may concern:

Be it known that I, JOSEPH L. KYLE, a citizen of the United States, residing at Glendale, Long Island, in the county of Queens and State of New York, have invented a new, original, and ornamental Design for a Blanket, of which the following is a specification, reference being had to the accompanying drawing, forming a part hereof, which drawing is a plan view showing my design.

The drawing illustrates the lower right hand

corner of the blanket and includes one-fourth of the area of a blanket which is multiplied symmetrically in the remaining three-quarters of the blanket, but with the living figures and animals so that they all appear to stand upright when viewed as in the drawing.

I claim:

The ornamental design for a blanket or similar article as shown and substantially as described.

JOSEPH L. KYLE.
